Primary Examiner — Bridget L Eland*Assistant Examiner* — Lauren McVey(57) **CLAIM**

I claim the ornamental design for a bell-shaped nasal dilator, as shown and described.

DESCRIPTION

FIG. 1 is a top left side perspective view of a bell-shaped nasal dilator showing my new design;

FIG. 2 is a front view thereof;

FIG. 3 is a rear view thereof;

FIG. 4 is a bottom plan view thereof;

FIG. 5 is a top plan view thereof;

FIG. 6 is a right side view thereof, the left side a mirror image thereof; and,

FIG. 7 is a second front view thereof, shown in an environment.

The broken lines in the drawings are directed to environment and form no part of the claimed design.
